BOTTLE CAP DISPLAY STRUCTURE

James P. H. Leavitt, Wayne, Pa., assignor to Container Corporation of America, Chicago, Ill., a corporation of Delaware

Application March 26, 1951, Serial No. 217,613

6 Claims. (Cl. 206—44.11)

1

This invention relates to containers and more particularly to containers constructed in a manner so as to permit the contents to be readily identified.

The principal object of the invention is to provide a shipping container, one or more of the exterior walls of which is adapted to receive, retain and conspicuously display one of a plurality of flanged articles to be packed in the container thus aiding in the prompt and accurate identification of the contents of the container.

A further object of the invention is to provide an arrangement in a container whereby a flanged article such as a pressure bottle cap may be inserted into an exterior wall of a container and retained in such relation with its identification bearing surface exposed on the exterior of the container.

In the drawing:

Fig. 1 is a perspective view of a paperboard container constructed in accordance with the invention and showing one wall thereof formed so as to display a bottle cap inserted therein;

Fig. 2 is a fragmentary sectional view on the line 2—2 of Fig. 1, illustrating the manner in which the flange of the bottle cap is retained between the inner liner sheet and outer liner sheet of a double-faced corrugated board;

Fig. 3 is a fragmentary view of a portion of the corrugated paperboard container wall showing a portion of the outer liner sheet cut away to show the manner of retaining the flanged edge portion of a bottle cap; and

Fig. 4 is a fragmentary plan view of a blank for a container such as illustrated in Fig. 1.

Referring to the drawings, the invention, as herein disclosed, is preferably applied to the type of paperboard known as double-faced corrugated paperboard which is composed of outer liner sheet 1, corrugated medium 2 and inner liner sheet 3. A conventional type of container is formed from such material, comprising side walls 10, 11, 12, and 13, each having a flap designated respectively as 14, 15, 16, and 17 defined from the side walls by the score lines indicated. When the container is set up and the flaps are folded into overlapping relation and secured in place, they constitute an additional wall of the container.

Any one or more of the walls of the container may be conditioned in accordance with this invention. A description of one wall so conditioned will suffice.

Side wall 13 is preferably formed with a substantially circular cut line 18 in its outer sur-

2

face, such cut line extending through the outer liner sheet 1 and through at least portions of the adjacent crests of the corrugations of the corrugated medium 2. The aperture 19 thereby formed in the outer surface portion of the side wall is appreciably smaller in diameter than the diameter of the flanged edge portion 20 of a conventional bottle cap 21 herein illustrated, the purpose being to retain the bottle cap in the aperture. It is obvious that the aperture need not be round, but may have any suitable configuration as long as there are sufficient bearing surfaces of the outer liner sheet 1 against the flanged edge portion 20 of the bottle cap 21 to retain such bottle cap in the aperture. Accordingly, when reference is made to the diameter of the aperture 19, it is understood to mean the distance across the bearing surfaces of the aperture.

The aperture 19 is preferably formed by a suitable die cutting tool which will cut through the outer liner sheet 1 and through portions of the adjacent crests of the corrugations of the corrugated medium 2. The corrugated medium within the aperture is preferably at the same time somewhat crushed or flattened to permit an easier entry of the flanged edge portion 20 of the bottle cap 21 into the aperture.

The top surface 22 of bottle cap 21 is customarily imprinted with identifying indicia.

In practice, after the container is filled with bottle caps and preferably prior to sealing of the container, a bottle cap 21 identical with those within the container is placed over the aperture 19 with its flanged edge portion upon the outer liner sheet 1. Pressure is then applied as with the thumb of the hand upon the top surface 22 of the bottle cap. By doing so the periphery of the outer liner sheet 1 immediately adjacent and surrounding the aperture 19 is temporarily displaced inwardly thereby effectively increasing the size of the opening and permitting the flanged edge portion 20 of bottle cap 21 to snap past the outer liner sheet 1 and to enter the space provided in the interior of the double-faced corrugated paperboard. Immediately after insertion of the cap flange the outer liner sheet 1 tends to spring back to its original condition.

The diameter of aperture 19, being appreciably less than the diameter of the flanged edge portion 20 of bottle cap 21, the edge portions of outer liner sheet 1 defining aperture 19 retain the bottle cap securely in position with its printed surface exposed at the exterior of the carton, thus indicating the contents thereof.

Since cut line 18 does not extend through inner liner sheet 3, it is obvious that there is no danger of the bottle cap being forced from its indicating position in the exterior wall of the carton into the interior of the carton.

It is to be understood that the invention is not limited in its use to bottle caps but is also adapted for use with flanged jar caps or similar flanged articles.

While the present description sets forth a preferred embodiment of the invention, certain changes may be made in the construction without departing from the spirit of the invention and it is therefore desired that the present embodiment be considered in all respects as illustrative and not restrictive, reference being had to the appended claims rather than to the foregoing to indicate the scope of the invention.

I claim:

1. In means for identifying articles of a shipment, a shipping container having a wall of corrugated paperboard comprising an outer liner sheet and an inner liner sheet and a corrugated sheet between and adhesively secured to the inner faces of said liner sheets, and an identifying article, said outer liner sheet being cut to provide an element severed therefrom approximately corresponding in outline to but appreciably smaller than the outline of said identifying article, the area of said inner liner sheet corresponding to said element being restrained against relative movement, said severed element remaining adhesively secured to said corrugated sheet and being displaced inwardly of said wall providing a corresponding aperture in said outer liner sheet and placing under compression between said inner liner sheet and said element the area of said corrugated sheet corresponding to said element, said identifying article being inserted in said aperture with the edge portion of said outer liner sheet about said aperture overlying peripheral elements of said article effective for retaining the latter in said aperture.

2. In means for identifying articles of a shipment, a shipping container having a wall of corrugated paperboard comprising an outer liner sheet and an inner liner sheet and a corrugated sheet between and adhesively secured to the inner faces of said liner sheets, and an identifying article, said outer liner sheet being cut to provide an element severed therefrom approximately corresponding in outline to but appreciably smaller than the outline of said identifying article, the area of said inner liner sheet corresponding to said element being intact with said inner liner sheet, said severed element remaining adhesively secured to said corrugated sheet and being displaced inwardly of said wall providing a corresponding aperture in said outer liner sheet and placing under compression between said inner liner sheet and said element the area of said corrugated sheet corresponding to said element, said identifying article being inserted in said aperture and confined between said element and the edge portion of said outer liner sheet about said aperture, said edge portion overlying peripheral elements of said article effective for retaining the latter in said aperture.

3. In means for identifying articles of a shipment, a shipping container having a wall of corrugated paperboard comprising an outer liner sheet and an inner liner sheet and a corrugated sheet between and adhesively secured to the inner faces of said liner sheets, and an identifying article, said outer liner sheet and said corrugated sheet being cut to provide an element severed from said outer liner sheet and said element corresponding in outline to but appreciably smaller than the outline of said identifying article, the area of said inner liner sheet corresponding to said element being intact with said inner liner sheet, said severed element remaining adhesively secured to said corrugated sheet and being displaced inwardly of said wall providing a corresponding aperture in said outer liner sheet and placing under compression between said inner liner sheet and said element the area of said corrugated sheet corresponding to said element, said identifying article being inserted in said aperture with the edge portion of said outer liner sheet about said aperture overlying peripheral elements of said article effective for retaining the latter in said aperture.

gated sheet being cut to provide an element severed from said outer liner sheet and approximately corresponding in outline to but appreciably smaller than the outline of said identifying article, the area of said inner liner sheet corresponding to said element being intact with said inner liner sheet, said severed element remaining adhesively secured to said corrugated sheet and being displaced inwardly of said wall providing

10 a corresponding aperture in said outer liner sheet and placing under compression between said inner liner sheet and said element the area of said corrugated sheet corresponding to said element, said identifying article being inserted in said aperture with the edge portion of said outer liner sheet about said aperture overlying peripheral elements of said article effective for retaining the latter in said aperture.

20 4. In means for identifying articles of a shipment of bottle caps and analogous articles of approximately circular outline, a shipping container having a wall of corrugated paperboard comprising an inner liner sheet and an outer liner sheet and a corrugated sheet between and adhesively secured to said liner sheets, and an identifying article of approximately circular outline, said outer liner sheet and said corrugated sheet being cut to provide a disc-like element severed from said outer liner sheet and of appreciably 25 less diameter than said identifying article, the area of said inner liner sheet corresponding to said element being intact with said inner liner sheet, said element remaining adhesively secured to said corrugated sheet and being displaced inwardly of said wall providing a corresponding aperture in said outer liner sheet and placing under compression between said inner liner sheet and said element the area of said corrugated sheet corresponding to said element, said identifying article being inserted in said aperture and confined between said element and the edge portion of said outer liner sheet about said aperture, said edge portion overlying circumferential elements of said article effective for retaining the latter in said aperture.

30 5. In article shipping and display means for disc-like articles, a shipping container having a wall of corrugated paperboard comprising an outer liner sheet and an inner liner sheet with a corrugated sheet between and adhesively secured to them, and a disc-like identifying article, said outer liner sheet and corrugated sheet being cut to provide a disc element severed from said outer liner sheet and adhesively secured to said corrugated sheet, the area of said inner liner sheet corresponding to said element being intact with said inner liner sheet, said element being of appreciably less diameter than said identifying article and providing a corresponding aperture in said outer liner sheet, said article being inserted in said opening by being placed over said aperture and pressed inward of said wall whereby at least a portion of said outer liner sheet contiguous to said aperture is temporarily displaced toward said inner liner sheet causing the effective diameter of said aperture to be temporarily increased to permit the article to snap into the aperture and said displaced portion of said outer sheet to return to its original position effective for retaining the article in said aperture.

35 6. In means for identifying articles of a shipment of bottle caps, a shipping container having a wall of corrugated paperboard comprising an inner liner sheet and an outer liner sheet and

a corrugated sheet between and adhesively secured to said liner sheets, and a bottle cap, said outer liner sheet being cut to provide an element severed therefrom approximately corresponding in outline to but appreciably smaller than the outline of said cap, the area of said inner liner sheet corresponding to said element being restrained against relative movement, said severed element remaining adhesively secured to said corrugated sheet and being displaced inwardly of said wall providing a corresponding aperture in said outer liner sheet and placing under compression between said inner liner sheet and said severed element the area of said corrugated sheet corresponding to said element, said bottle cap being inserted in said aperture and confined between said severed element and the edge portion of said outer liner sheet about said aperture, said edge portion overlying peripheral elements of said bottle cap effective for retaining the latter in 20 said aperture.
